FIG. 5.

UNITED STATES PATENT OFFICE.

JAMES J. DONOVAN, OF PEABODY, MASSACHUSETTS.

STEERING DEVICE FOR POWER-BOATS.

SPECIFICATION forming part of Letters Patent No. 792,121, dated June 13, 1905.

Application filed August 31, 1904. Serial No. 222,809.

To all whom it may concern:

Be it known that I, JAMES J. DONOVAN, a citizen of the United States, and a resident of Peabody, in the county of Essex and State of Massachusetts, have invented certain new and useful Improvements in Steering Devices for Power-Boats, of which the following is a specification.

This invention relates to improvements in steering devices for power-boats; and it is carried out as follows, reference being had to the accompanying drawings, wherein—

Figure 1 is a plan view of the forward end of a power-boat with my improved steering device attached. Fig. 2 is a detail top plan view of the said steering device. Fig. 3 is a longitudinal section on the line 3 3 shown in Fig. 2. Fig. 4 is a cross-section on the line 4 4 shown in Fig. 2, and Fig. 5 is a cross-section on the line 5 5 shown in Fig. 2.

Similar letters refer to similar parts wherever they occur on the different parts of the drawings.

In Fig. 1, A represents the forward end of a power-boat, on which B is the forward deck portion, as usual.

C is the steering-wheel, attached in any suitable manner to the spindle D, the forward end of which is journaled in a bearing E, integral with which is a horizontal sleeve E', in which is guided a rod F, having a toothed rack F' on its upper side engaging with a toothed pinion D', secured in a suitable manner to the forward end of the wheel-spindle D, as shown.

The rack-rod F is connected at its ends to cords G G, leading over suitable pulleys g g to the rear connecting device of the rudder-post in any suitable or well-known manner.

The ends of the sleeve E' are journaled in blocks H H, adapted to be secured in any de-

sired position, horizontally inclined or vertical to the deck or other portion of the boat, as may be desired. Each of said blocks H is slotted, as shown at h, Figs. 3 and 4, and provided with a clamping-screw H', by means of 45 which the sleeve E' can be clamped firmly in any desired position, so as to hold the bearing E, its adjustable spindle D, and wheel C in any suitable position desired by the operator of the steering device.

The rear end of the bearing E is slotted at e and provided with a binder-screw I for the purpose of clamping the spindle D and its pinion D' firmly in position whenever it is desired to hold the rudder in a central position 55 while steering the boat in a linear direction, as may be desired in going in a straight course.

f f are stop projections secured to the ends of the rack-spindle F, so as to prevent the latter from being moved beyond the ends of the 60 bearing-sleeve E' during the turning of the wheel C. K is a removable shield secured to the bearing E for the protection of the pinion D' from dust, &c.

What I wish to secure by Letters Patent and 65 claim is—

The herein-described steering device, consisting of a wheel-carrying spindle, a pinion attached thereto, a longitudinally movable rack-rod actuated by the pinion, a guide-sleeve 70 in which said rack-rod is movable means for adjustably securing said sleeve and means for adjustably securing the spindle and pinion in the required position substantially as set forth.

In testimony whereof I have affixed my signature in presence of two witnesses.

JAMES J. DONOVAN.
